UNITED STATES PATENT OFFICE.

ALLISON E. PALMER, OF WINSTED, CONNECTICUT, ASSIGNOR TO BELDING BROS. & CO., OF NEW YORK, N. Y., A CORPORATION OF NEW YORK.

DENTAL FLOSS CONTAINER.

Application filed November 7, 1924. Serial No. 743,320.

To all whom it may concern:

Be it known that I, ALLISON E. PALMER, a citizen of the United States, and resident of Winsted, county of Litchfield, and State of Connecticut, have invented certain new and useful Improvements in Dental Floss Containers, of which the following is a specification.

The invention relates to dental floss containers, and particularly to such containers in which a spool or holder of dental floss is mounted within a glass dome, through which it may be seen, and through an opening in which the dental floss is extended, for use.

In such devices the glass dome has previously been removably mounted by pressing its lower edge down into a shallow circular groove in the base member, in which it has been held by friction, the material of the base on the inside of the groove pressing against the inside of the circular wall of the dome. If this base material is somewhat resilient, such as cork, the dome will be held more or less effectively in place. In actual practice, however, such devices are often unsatisfactory because the cork or other material relied upon to effect the friction joint does not fit properly, or becomes worn, or varies for other reasons. As a result the dome will not be held tightly, and is liable to fall off and be broken.

An object of my invention is the provision of means whereby these defects will be obviated, while providing an efficient container with a removable dome which will be positioned and firmly held to its base. Another object is the provision of such a container in which the dental floss will be attractively displayed, which container will be simple and inexpensive in construction, and in which the dome may be removably secured in position in a simple and positive manner.

I accomplish these objects by providing the base member with an upstanding annular flange which is screw-threaded on the interior, and providing the dome with an external screw-thread, so that it can be screwed down inside the flange. Preferably the base member is provided with an upstanding cylindrical boss on which the spool of dental floss is supported, so that the spool will be raised sufficiently to enable the floss or silk to be entirely displayed through the glass, this boss being surrounded by an annular space into which the lower end

of the glass dome extends. The threaded flange on the base will preferably have its outer surface continuous with the outer surface of the base proper, preferably in a graceful curve, in order to enhance the attractive appearance of the container, the upper edge of the flange forming an attractive finish for the bottom of the glass dome. Preferably also the base and its flange are formed of wood, which forms a somewhat resilient support into which the glass dome is screwed, thus preventing damage in case of any unequal variations in diameter of the parts, caused by unequal contraction or expansion of the parts upon changes in temperature.

The invention consists in the construction and combination of parts which will be more fully set forth hereinafter and which will be particularly pointed out in the appended claims.

In order that the invention may be more clearly understood attention is hereby directed to the accompanying drawings forming part of this application and illustrating one embodiment of the invention which is at present preferred. In the drawings—

Fig. 1 is a vertical section through a dental floss container embodying the invention;

Fig. 2 is a horizontal section taken on line 2—2 of Fig. 1, and

Fig. 3 is a bottom plan view of the device.

Referring to the drawings, the base member 1 is preferably formed of wood and has an upstanding annular flange 2, the outer surface of which is preferably formed continuous with the outer surface of the base proper. This flange is provided with an internal screw-thread, as indicated at 3. 95

The dome 4 is preferably made of glass and is provided with an opening 5 therethrough, through which the silk or dental floss 6 may be extended for use and withdrawn directly from the spool. The lower edge portion of the cylindrical wall of dome 4 is provided with an external screw-thread which is adapted to be screwed into the internal thread 3 of flange 2. 100

Base member 1 is provided with a seating surface for the spool 7 on which the dental floss is mounted. This seating surface preferably takes the form of a raised boss such as the cylindrical boss 8 on which spool 7 may be mounted, this boss being sur- 110

rounded by an annular space or groove 9 into which the lower end of the glass dome extends. Preferably the dome will screw down until its bottom edge rests firmly on the horizontal surface 10 forming the bottom of the annular groove or space 9. When the spool is so mounted it will be raised high enough, by the support 8, so that all of the dental floss on the spool will be visible through the glass wall of dome 4. Preferably dome 4 is of such a size as to contain the spool quite snugly so that the spool will rotate within the dome as the dental floss is unreeled from it, the spool being supported laterally and guided in its rotation by the cylindrical wall of the dome.

It will be noted that the outer surface of the base 1 is preferably formed with a graceful curve, such as is indicated at 11, the upper edge portion of which, constituting the outside surface of flange 2, preferably comes into parallelism with the outer surface of dome 4. The flange will accordingly form an attractive finish for the bottom of the dome. A disc 12 is shown secured to the bottom of base 1 with an overhanging edge, to form a cutter for the dental floss 6.

With the structure as above described, it will be noted that a simple and convenient form of base is provided which may be readily threaded on and off in respect to the glass dome and without interference with the end of the dental floss which passes out through the aperture 5 at the upper part of the dome and remote from the base. In assembling the device, the end of the floss may be first threaded through the aperture and the spool then dropped into the dome; thereafter the base member may be readily screwed on without interference with the spool or floss. When in working position the floss throughout the length of the spool is exposed to view through the glass dome by reason of the use of the support 8 which retains the spool in a position sufficiently elevated to insure this result. Furthermore, the end of the floss extends directly from the spool to the aperture through the glass and it is entirely visible at all times and comes into contact with none of the container parts other than the glass. This fact insures the sanitary condition of the device inasmuch as the floss comes in contact with no parts which are subject to corrosion or have irregular surfaces which might retain dust or dirt.

It is not desired to limit the invention to

all of the specific details herein described since it will be obvious to those skilled in the art after understanding the invention that various modifications may be made without departing from the scope of the invention and I aim, therefore, in the appended claims to cover all such possible modifications.

What I claim is:

1. In a dental floss container, the combination of a base having an upstanding annular flange formed with an integral screw-thread, and a portion inside said flange on which a spool of dental floss is adapted to be supported, and a glass dome having an opening therethrough for the passage of dental floss directly from the spool, and having an external screw-thread about its lower edge portion, adapted to screw into said flange, to removably surround the spool.

2. In a container for a spool of dental floss, the combination of a base having an upstanding annular flange formed with an internal screw thread, an annular space being provided inwardly of said thread, a glass dome having an aperture through its upper portion for the passage of dental floss therethrough directly from the spool, said dome having an external screw thread about its lower edge portion adapted to screw into said flange and extend into said annular space, and an elevated portion within the dome on said base and inside said annular space on which the spool of dental floss is supported with the floss entirely exposed to view through the glass dome.

3. In a container for a spool of dental floss, the combination of a base having an upstanding annular flange formed with an internal screw thread, an annular space being provided inwardly of said thread, a glass dome closely embracing the spool but permitting the spool to freely revolve therein, said dome having an aperture through its upper portion for the passage of dental floss therethrough directly from the spool and having an external screw thread about its lower edge portion adapted to screw into said flange and extend into said annular space, and an elevated portion within the dome on said base and inside said annular space on which the spool of dental floss is supported with the floss entirely exposed to view through the glass dome.

In testimony whereof I have signed my name to this specification.

ALLISON E. PALMER.
